Primary Examiner — Prabhakar Deshmukh(74) *Attorney, Agent, or Firm* — Mark D. Miller**CLAIM**

I claim the ornamental design for a garment bag, as shown and described:

DESCRIPTION

FIG. 1 is a front perspective view of the garment bag showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front perspective view of the garment bag in a partially folded condition; and

FIG. 9 is a front perspective view of the garment bag in another partially folded condition.

FIG. 10 is a front perspective view of the garment bag in an open condition showing internal flaps folded out;

FIG. 11 is a front perspective view of the garment bag in an open condition showing internal flaps folded in; and,

FIG. 12 is a top perspective view of the garment bag in an open condition showing internal flaps folded in.

The broken lines in the figures are for illustrative purposes only and form no part of the claimed design.
